Primary Examiner — Patricia Palasik*(74) Attorney, Agent, or Firm* — Faegre Baker Daniels, LLP(57) **CLAIM**

The ornamental design for film-forming apparatus, as shown and described.

DESCRIPTION

FIG. 1 is a front perspective view of a first embodiment of a film-forming apparatus showing our new design;
FIG. 2 is a rear perspective view thereof;
FIG. 3 is a front view thereof;
FIG. 4 is a rear view thereof;
FIG. 5 is a top plan view thereof;
FIG. 6 is a right side view thereof;
FIG. 7 is a left side view thereof;
FIG. 8 is a front perspective view of a second embodiment of a film-forming apparatus showing our new design;
FIG. 9 is a rear perspective view thereof;
FIG. 10 is a front view thereof;
FIG. 11 is a rear view thereof;
FIG. 12 is a top plan view thereof;
FIG. 13 is a right side view thereof; and,
FIG. 14 is a left side view thereof.
